UNITED STATES PATENT OFFICE.

CLARENCE H. WILKES, OF GLOVERSVILLE, NEW YORK, ASSIGNOR TO LOCK-EDGE MACHINE CORPORATION, OF GLOVERSVILLE, NEW YORK, A CORPORATION OF NEW YORK.

GLOVE.

Application filed November 20, 1922. Serial No. 602,232.

To all whom it may concern:

Be it known that I, CLARENCE H. WILKES, a citizen of the United States, residing at Gloversville, in the county of Fulton and 5 State of New York, have invented certain new and useful Improvements in Gloves; and I do hereby declare the following to be a full, clear, and exact description of the same, reference being had to the accompanying drawings, forming part of this specification.

This invention relates to gloves and particularly to the seams for fitting up and for closing the fingers. The object of the present invention is to provide a glove in which the fingers are closed in such manner as to form a flat seam of neat appearance and one which will not ravel out even though one or more of the threads forming the seam 20 should be broken.

At the present time there are four methods of closing the fingers of gloves, namely: out-seam, wherein a ridge is formed beyond the line of stitching; in-seam, 15 wherein the glove is sewn while wrong side out and then turned placing the ridge inside of the glove where it will not be seen; over-stitching, wherein the two raw edges are whipped over or crocheted with a chain 25 stitch, this stitching almost invariably being made on a cup machine; and pique, which forms a flat seam made with a single needle, the stitching, therefore, being of the chain 30 type, which will rip to a very considerable extent, should a single thread be broken.

In addition to the above there are post type sewing machines which will close the fingers of gloves with either a chain or a lock stitch, the latter being quite rare but 40 well shown in Patent No. 1,049,430, granted to me January 7, 1913. The glove of the present invention is a very material advance in the art over a glove made by the machine of the patent cited in that in the present 45 glove no free edge is left to become turned over so that it will quickly become soiled and dirty; furthermore, the stitching will not ravel out in a glove made in accordance with the present invention even though one 50 or more of the threads of the seam should become broken, this advantage being due to the locking of each of the twin needle stitchings and the further locking of the longitudinal stitchings by the one or more 55 cover threads, when the latter are used.

In the drawings,—

Figure 1 is a view of a glove made in accordance with the present invention.

Fig. 2 is a view of the stitching in its preferred form, using two cover threads. 60

Fig. 3 is a similar view, but omitting the two cover threads.

Fig. 4 is a view on line 4—4 of Fig. 2.

Fig. 5 is a view on line 5—5 of Fig. 2.

The seam by which the glove of the present invention is made is itself new and the machine for making this stitch is covered in my copending application Serial No. 607,380, filed December 16, 1922. This stitch is formed in a single operation on a post 70 type machine having two needles working vertically within the post, the thread from each of the twin needles cooperating with a bobbin thread in the usual way, so that the twin needles form two parallel lock-stitch 75 seams. Preferably, although not essential, a plurality of cover threads are laid on the seam by means of simultaneously operating loopers, the cover threads each extending alternately to the sides of the two parallel 80 lock-stitch seams and in addition crossing each other between the lock-stitch seams in an X formation, as seen in Fig. 2.

In this preferred type of seam even though one of the needle threads and its 85 cooperating bobbin thread should be cut or broken, the stitching would not ravel out to such an extent as to cause even a small rip in the glove, as the remaining lock stitch seam, reinforced as it is by the two 90 cover threads, would effectively prevent the formation of a hole.

The glove is in general of the usual type having a body 10 with the customary integral fingers 11 and an inserted thumb 12. 95 The closing seam 14 of the thumb and the seam 15 which joins the fingers of the body to their forgings 17 are of the type shown in Fig. 2, as is the finger closing and side seam 18, and the various gusset or quirk seams. 100 It is preferable, in general, however, to hem the glove as at 20, with a single lock-thread stitch, if a facing is used.

Referring now to Fig. 2, n^1 and n^2 are the two needle threads and b^1 and b^2 are the co- 105 operating bobbin threads, the latter, as previously mentioned being applied to the goods from above while the needle threads are applied from beneath, that is through the post. The looper threads 1' and 1² are 110

parallel to the lock-stitch threads for a portion of their extent, as for example at 22 and 23 and then extend between adjacent needle holes to cross each other as at 24, forming a very effective lock, the cross of the X being practically on a line with the center of the seam as a whole.

It will be noted that contrary to usual practice the raw edge of the outer lap of the material, as 25, is not positioned midway between the two seams 26 and 27, but lies close to the seam 27, so that the two looper threads, as they cross the raw edge of the leather or other material, are spaced apart, thereby to hold more effectively the raw edge of the outer lap of the material. As will be seen from Fig. 5, the stitching 26 extends through both of the pieces of material, while the stitching 27 extends only through the bottom or inner lap, the raw edge 30 of which, in the finished glove extends somewhat beyond the stitching 26 and is subject to the same turning over as is the usual outside edge, but since the edge 30 is invariably inside the glove, this does not detract in any way from the appearance of the finished article.

Since the positioning of the stitching 27 tight to the raw edge 25 of the outer lap of the material is secured either by a gage or by the positioning of the side-by-side twin needles, it would not be possible to form a flat seam with a locked-in raw edge by re-sewing a glove closed with a single stitch even if it were possible to re-sew a flat finger closing seam, a feat which to my knowledge, has not yet been accomplished.

While the use of two crossed cover threads is much preferred, neither or both are essential, and a very satisfactory glove may be made by the use of the four-thread seam made by the twin needles, such a seam being shown in Fig. 3, which may be considered as a modification of the preferred seam.

45 What is claimed is:

1. A glove characterized by the finger closing seam being flat and formed by two independent rows of stitching and a cover thread, said independent rows of stitching as they appear on the inside of the glove being in stitches positioned longitudinally only of the seam and said cover thread being positioned on the outside of the glove only and crossing the raw edge of the outer lap of the material as said cover thread passes alternately from one of said independent

rows of stitching to the other, whereby a seam is formed having no stitching on the inside surface of the glove positioned transversely to the line of the seam.

2. A glove characterized by the finger closing seam being flat and formed by two independent parallel rows of locked stitching one on each side of the raw edge of the outer lap of the material, and a cover thread, 65 said cover thread crossing the raw edge of said outer lap as said cover thread passes from one row of lock stitching to the other, one thread only of each independent row of locked stitching appearing on the inside of 70 the glove with the individual stitches of each last mentioned threads lying longitudinally only of the seam, and said cover thread appearing entirely on the outside of the glove, whereby a seam is formed having 75 no transverse stitching on the inside surface of the glove.

3. A glove characterized by the finger closing seam being flat and formed by two independent parallel rows of locked stitching positioned on opposite sides of the raw edge of the outer lap of the material and by a cover thread passing over the raw edge of the outer lap of the material and being locked in place by each of said rows of 80 stitching, whereby the raw edge of the outer lap of the material is neatly and effectively retained by the cover thread adjacent where said cover thread is locked in place by the row of stitching nearest the raw edge of 85 the outside lap, the cover thread stitching being located on the exterior of the glove.

4. A glove characterized by the finger closing seam being flat and being formed by two independent parallel rows of locked 95 stitching positioned on opposite sides of one raw edge of the outer lap of the material and a plurality of cover threads locked in place on the material by each of said parallel rows of locked stitching, the cover threads 100 crossing one another between the two rows of locked stitching but being spaced apart where they cross the raw edge of the material, whereby the raw edge of the outer lap of the material is neatly and effectively retained by the cover threads adjacent where they are locked in place by the row of stitching nearest the raw edge of the outside lap, the cover thread stitching being located on the exterior of the glove.

CLARENCE H. WILKES.
